Primary Examiner — George D. Kirschbaum

Assistant Examiner — Maria J Edwards

(57) **CLAIM**

The ornamental design for a mobile phone shell, as shown and described.

DESCRIPTION

FIG. 1 is a perspective view of a mobile phone shell showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, shown in a position of use; and,

FIG. 10 is a perspective view thereof, shown in a second position of use.

The broken lines in the drawings illustrate portions of the mobile phone shell and form no part of the claimed design.

1 Claim, 10 Drawing Sheets
